UNITED STATES PATENT OFFICE.

JOHN W. WHITE, OF BUFFALO, NEW YORK.

WHEEL.

Application filed September 2, 1922. Serial No. 585,952.

This invention relates to an improvement in wheels and more particularly in wheels of the disc type and in the means for demountably securing the rims to the wheel 5 discs.

In such wheels it is essential that the rim be easily and quickly demounted and in order to attain that result, the rim is held in place by a clamping action, the rim being 10 located between the periphery of the disc and any suitable fastening means bolted to the disc so that as the bolts are tightened the rim is clamped in place. The peripheral edge of the disc is flanged to engage one of 15 the outer contours of the rim while the fastening means, either a ring or a series of plates engage the other outer contour.

However, it has been determined that the rim has a pronounced tendency to weave; 20 that is to say, when any force causes the rim to move transversely of the wheel plane, the point of the rim diametrically opposite that at which the force is applied also moves in the same direction, while the points halfway 25 between the first points move in the opposite direction. While such movement is commonly referred to as transverse to the wheel plane, a turning upon the median line of the rim as a fulcrum also takes place so that 30 there results a compound movement. Thus in such transverse movement, one edge of each portion will turn outwardly and the other inwardly relative to the median line of the rim.

Such interaction in wheels made in accordance with the practice generally followed, will, of course, be transmitted thru the disc flange and the fastening means to the disc itself so that the disc must be made 40 of sufficient strength to resist this rim weave as well as to support the vehicle and resist the lateral strains which arise in travelling over the road. The result of this movement is to increase the fatigue of the disc metal at the hub. Because of such strains, 45 the diameter of the hub flange is limited.

The chief object of this invention is to provide a disc wheel in which the rim weave is not transmitted to the wheel disc and more 50 particularly to provide in such wheel a de-

mountable rim having a flange along its median line on the inner side which flange is clamped between the disc and the fastening means. In other words, in place of the rigid clamping connection between the disc 55 and the rim there is provided a connection having substantially the action of a ball and socket joint so that the weave of the rim is independent of the disc. A further object is to provide a disc wheel in which the peripheral unsprung weight is reduced which 60 is simpler and can be made at a reduced cost and by the use of which the time of changing a demountable rim is reduced and the ease of performing such operation is increased. 65

Another object of this invention is to provide a demountable rim having along the median line, an inwardly projecting bead by which the rim can be mounted upon a 70 wheel.

Other objects will appear from a consideration of the following specification taken in connection with the accompanying drawing which forms a part thereof and in 75 which

Fig. 1 is a transverse section of the rim portion of a disc wheel embodying this invention showing a clamping ring which is held in position by a series of bolts. 80

Fig. 2 is a similar view of another part of the rim portion of such wheel showing the relation of the valve stem to the other elements.

Fig. 3 is a similar view of another part 85 of the rim portion of such wheel showing the relation of the disc and clamping ring to the rim locking plate.

Fig. 4 is a bottom plan view of that part 90 of the rim shown in Fig. 3.

Fig. 5 is a longitudinal section of such part taken along the line 5-5 of Fig. 4; and

Fig. 6 is a view similar to Fig. 1 of a disc wheel in which a series of fastening clamps 95 is used in place of a clamping ring.

Referring to the drawings, the reference numeral 10 is used to designate the disc of a disc wheel embodying one form of this invention. For purpose of illustration the form of disc shown in my co-pending ap- 100

plication Ser. No. 569,384 has been selected, certain changes in the rim contacting portions being of necessity made.

Mounted at the outer periphery of the disc, 10, is a rim, 11 which is shown of the straight side type, the formation of both sides of the rim being the same so that the rim can be reversed if desired without any change in the adjustments. Formed on the inner side of the rim along the median line, 12, is a bead, 13, that shown being of the V-shape. This bead, as will be set forth later, forms a shoulder by which the rim is clamped to the disc.

15 A clamping ring, 14, is secured by a series of bolts, 15, to the disc, 10, suitable blisters, 16, being formed in the disc on which the ring, 14, rests. The ring, 14, is approximately C-shaped in cross-section, its inner flange, 17, resting on the blisters, 16 and its outer flange, 18 which is somewhat shorter than the inner flange bearing against the bead, 13.

At the periphery of the disc, 10, is formed 25 a flange, 19, the connection portion, 20, being rounded. This portion, 20 also bears against the shoulder, 13 so that it is clamped between the disc, 10 and the clamping ring, 14. The radial portion 21 of the disc is at 30 approximately the median line of the wheel so the line, 12, indicates the median line of the wheel and also the median line of the rim. Thus, the rim is held in position upon the disc by the contacts of the portion, 20, 35 of the disc, and the flange, 18 of the ring upon the bead 13. Since the contacting surfaces are both curved, it must follow that the rim is held upon two separated lines of contact, which are adjacent to and equally dis- 40 tant from the median line, 12. Hence, the main tendency of the rim to weave will take place without being transmitted to the disc, the rim being simply cradled between these circumferential lines of contact, and oscil- 45 lated around the median line.

Since the radial portion, 21, of the disc is at the median line, 12, of the wheel, it is slotted and pressed back at 22 to permit the valve stem 23 of the tire to project radially 50 thru the hole, 23, in the rim and to lie in the median plane in front of the disc. When the parts are assembled, the lock nut is tightened against 22 and the ring, 14, to hold the stem in position. The disc, 10, is 55 also forced back at 24 so that the chuck of the air hose can be applied without bending the stem or scarring the disc.

After the ring, 14, is removed, the tire can be removed from the disc with the rim with- 60 out deflation.

The clamping action of the curved por- 65 tion 20, of the disc and the ring, 14, upon the bead, 13, is sufficient to insure rotation of the rim with the disc but in order to pro- vide further driving means, the portion, 20,

and ring 14 are notched at 25, and 26, see Fig. 3, to receive the locking plate, 27. The rim 11 is preferably of the split type, the ends 28 and 29, being connected in the usual manner by the plate 27, which is riveted 70 to the end 28 and enters a slot, 30 in the end 29. As shown in Figs. 4 and 5, the bead 13 ends at each side of the plate, 27.

In place of a clamping ring, 14, a series of clamping lugs, 37, held by bolts, 38 may 75 be employed if desired. These lugs function in the same manner as the ring, 14, the spaces between them being insufficient to interfere with the weaving of the rim.

While certain embodiments have been 80 shown and described, they were chosen for illustration only and it will be understood that I am not limited thereby since other embodiments can be made without departing from the spirit and scope of this invention as set forth in the following claims. 85

Having thus set forth my invention what I claim as new and for which I desire the protection of Letters Patent is as follows:

1. A disc wheel, comprising a wheel disc, 90 a rim, having an inwardly projecting bead adjacent the median line, a clamping ring, bolts for securing said ring to said disc, said disc having a curved portion, said bead being between said portion and said ring and 95 said portion and ring bearing against the sides of said bead and clamping said bead between them along single lines of contact at opposite sides of the median line to affix said rim to said wheel, the bolts securing 100 said ring to said disc being inward of said bead.

2. In a disc wheel, a disc, the outer portion of which is within the median line of the wheel, a rim having an internal bead 105 integral therewith and at the median line thereof, and clamping means carried by said disc and co-acting with the peripheral face thereof to engage said rim bead along single lines of contact at opposite sides of 110 the median line and hold said rim in place.

3. A disc wheel comprising a wheel disc, a rim and means for clamping said rim in position upon said disc, said rim having a V shaped bead formed on its inner periphery 115 adjacent the median line, said disc having at its periphery a flange connected to the body of the disc by a curved portion, said clamping means having a curved flange, the parts being so assembled that the rim bead is engaged by the curved portion of said disc and the curved flange of said ring at opposite sides of the median line whereby since in cross section the engaged sides of the bead are straight while the engaging parts 120 are curved the rim is supported upon two separated lines of contact.

4. A disc wheel comprising a wheel disc, a rim having an inner V shaped bead adjacent the median line and means clamping 130

said rim to said disc, said disc and clamping means so engaging said bead at opposite sides of the median line as to permit a weaving movement of said rim relative to said disc and clamping means.

5. A disc wheel, comprising a wheel disc, a rim having an inwardly projecting bead along its median line, and clamping means,

said bead being between said disc and said clamping means and said disc and means bearing against the sides of said bead along single lines of contact at opposite sides of the median line to hold said rim upon said wheel.

In testimony whereof, I affix my signature.

JOHN W. WHITE.
